RAILWAY CAR COUPLER HAVING MEANS TO PREVENT VERTICAL DISENGAGEMENT

Frank H. Kayler, Alliance, Ohio, assignor to American Steel Foundries, Chicago, Ill., a corporation of New Jersey

Application February 21, 1951, Serial No. 212,110

15 Claims. (Cl. 213—153)

1

This invention relates to railway car couplers and more particularly to automatically operated knuckle type couplers such as are recognized as standard equipment by the Association of American Railroads, or as used in some foreign countries which have adopted the knuckle type of coupler.

A primary object of the invention is to prevent accidental uncoupling resulting from relative vertical movement between mated coupler heads.

Another object of the invention is to prevent vertical separation by means adaptable to knuckle type couplers having certain special features of design, and also to provide an efficient design of interlock shelf with minimum obstruction to cleaning operations in the finishing of coupler castings.

Another object of the invention is to facilitate coupling of couplers which are at different levels.

A further object of the invention is to reinforce the throat of a coupler head at the midpoint between its guard arm and knuckle pivot ears.

A more specific object of the invention is to devise a novel coupler head having a shelf underlying its throat, said shelf having one or more levels or ledges engageable with the knuckle of a mating coupler to facilitate coupling and to prevent accidental uncoupling.

Another object of the invention is to devise an arrangement such as above described wherein relative vertical and vertical angling movements between the mated couplers are accommodated.

Still another object of the invention is to arrange the forward edge of the coupler head shelf in a vertical plane approximately tangential to the pivot openings in the coupler head ears, and to connect the shelf between the bottom ear and the coupler front face at a point approximating the point of tangency of the flat front face portion with the base radius of the guard arm, thereby affording maximum strength for support of the nose of a mated coupler knuckle and accommodating all positions of mated couplers.

The foregoing and other objects and advantages of the invention will become apparent from a consideration of the following specification and the accompanying drawings, wherein:

Figure 1 is a bottom plan view of mated coupler heads embodying a preferred form of the invention, the heads being shown in extreme position of horizontal angling;

Figure 2 is a top plan view of the structure shown in Figure 1, under buffing conditions;

2

Figure 3 is a top plan view similar to Figure 2 but showing the mechanism under pulling conditions;

Figure 4 is a sectional view on the line 4—4 of Figure 3 with both couplers shown in condition of maximum upward angling;

Figure 5 is a sectional view similar to that of Figure 4, but showing the couplers level under conditions of maximum vertical offset;

10 Figure 6 is a sectional view on the line 6—6 of Figure 1;

Figure 7 is a fragmentary front elevational view of one of the couplers shown in Figure 1;

15 Figure 8 is a fragmentary side elevational view taken on the line 8—8 of Figure 7;

Figure 9 is a top plan view of the couplers shown in Figure 1 during a coupling operation;

20 Figure 10 is a side elevational view of the structure shown in Figure 9 partly in section on the line 10—10 thereof and showing the couplers under conditions of maximum vertical offset;

25 Figures 11 to 17 illustrate a modification of the invention, Figure 11 being a bottom plan view comparable to Figure 1, Figure 12 being a top plan view comparable to Figure 2, Figure 13 being a top plan view showing the mechanism under pulling conditions such as those shown in Figure 3, Figure 14 being a sectional view on the line 14—14 of Figure 13 with both couplers shown in condition of maximum upward angling, Figure 15 being a sectional view similar to that of Figure 14 but showing the couplers level under conditions of maximum vertical offset, Figure 16 being a fragmentary front elevational view of one of the couplers shown in Figure 11, and Figure 17 being a fragmentary side elevational view taken on the line 17—17 of Figure 16.

30 Describing the invention in detail and referring first to the embodiment thereof illustrated in Figures 1 to 10 inclusive, mated couplers are generally designated in Figure 1 as 1 and 2 respectively. Each coupler comprises a head 3 having a guard arm 4 at one side thereof, and having top and bottom ears 6 and 8 at the opposite side thereof.

35 A knuckle 10 of each coupler extends between its ears 6 and 8 and is pivoted thereto by a pin 14. Each head also comprises a throat 16 between its guard arm 4 and its pivot pin 14, the throat having a contour complementary to and engageable with a nose 18 of the mating coupler knuckle 10 when the couplers are subjected to buffing forces, as illustrated in Figure 2 and as is well known to those skilled in the art. It may be noted that the above de-

40 scribed construction is conventional and is thus

not shown in detail, except as combined with the novel interlock means hereinafter described.

Each coupler head 3 is provided with an interlock shelf or web 20 underlying its throat 16, the forward edge of the shelf as best seen in the bottom plan view of Figure 1 lying in a plane approximately tangential to the coupler head pivot pin 14 and the openings in the ears 6 and 8 for said pin. The forward edge of the shelf 20 extends linearly along this plane from its juncture with the bottom ear 8 of the coupler head to a point in the region of the guard arm 4 and then curves forwardly at 21 (Figure 1) to merge with the bottom of the guard arm. The rear edge of the shelf 20 is connected to a web or leg 22 depending from the bottom of the coupler head 3 and extending arcuately from beneath the bottom ear 8 following approximately the contour of the throat 16 to the forward edge of the guard arm 4, as will be best understood by a comparison of Figures 1, 4 and 7; and the shelf 20 is reinforced by a rib 24 depending therefrom and having a segment 25 extending diagonally with respect to the longitudinal vertical center plane of the coupler head. The rib segment 25 extends across the shelf, beneath the throat 16 approximately midway between the merger of the throat with the guard arm 4 and the merger of the throat with the pivot ears 6 and 8. The rib segment 25 is connected to an angularly related rib segment 26 which extends along the forward edge of shelf 20 and merges with the bottom ear 8.

Each shelf 20 is adapted to underlie the knuckle 10 of a mated coupler, as clearly shown in Figure 1, wherein it will be seen that the shelves 20 of the respective couplers 1 and 2 underlie each other's knuckles 10 under conditions of maximum angling. Figures 2 and 3 illustrate conditions of maximum buff and pulling, respectively, and Figure 5 illustrates the manner in which the shelf 20 of coupler 2 engages the knuckle 10 of coupler 1 under pulling conditions and maximum vertical offset indicated at A in Figure 5.

Figure 4 illustrates both couplers 1 and 2 in a position of extreme upward angling and it will be seen in this figure that the upper rear edges of the knuckles 10 contact each other and the lower forward edges of the knuckles 10 contact the front faces of the mating coupler heads at 28 thereby limiting such upward angling without contact between the forward edges of the shelves 20 thereby preventing damage thereto. It will also be apparent that under a combination of vertical offset, as in Figure 5, with vertical angling, as in Figure 4, the limiting contact of the lower knuckle 10 will be against the web 22 of the related shelf 20. Inasmuch as the webs 22 are set back from the faces 28, increased angling is permitted under these conditions, but clearance is still maintained between the adjacent faces of the shelves 20.

Each shelf 20, as best seen in Figure 7 and in the illustration of coupler 2 in Figure 9, comprises an upper ledge or level 30 and also comprises a lower ledge or level 31 connected by a sloping diagonal wall or surface 32 to the upper ledge 30 along the forward edge of the rib segment 25.

The ledge 30 extends at an angle to the longitudinal vertical center plane of the coupler and joins the throat 16 at a point inwardly of the juncture of the throat with the guard arm, and the sloping surface 32, as best seen in Figure 9, extends to a point beneath the throat 16 at approximately the tangent point of the flat face of the throat to the base radius of the guard arm 4.

Figures 9 and 10 also show the manner in which the nose 18 of an open coupler knuckle 10 engages the lower ledge 31 during a coupling operation in the event that one of the couplers, as for example the coupler 1, in the illustration of Figure 10 is lower than the other during such a coupling operation.

It will be readily understood, as shown in Figures 9 and 10, that as the couplers are coupled or mated the knuckle nose 18 of the coupler 1 which is lower than the coupler 2, slides up the sloping wall or surface 32 of the coupler 2 and seats on the upper ledge or level 30 to engage the throat 16 of coupler 2 and complete the coupling operation as shown in Figure 2.

Figures 11 to 17 illustrate a modification of the invention wherein parts corresponding to those of the previously described embodiment are illustrated by corresponding numerals. It will be noted that in the modification the shelf 20 is a one level structure which, as best seen in Figures 11 to 13, is adapted to underlie the nose 18 of the mated coupler in all positions of horizontal angling, pulling, and buffing.

The extreme forward edge of the shelf 20 is in a plane approximately tangential to the coupler head pivot pin and its complementary openings in the ears 6 and 8. The forward edge of shelf 20 extends at an angle to this plane to the throat 16 joining the web 22 therebeneath at a point inwardly of the juncture of the throat with the guard arm 4, approximately beneath the tangent point of the flat face of the throat 16 to the base radius of the guard arm 4.

The rear edge of the shelf 20 is connected to the web or leg 22 depending from the bottom of the coupler head 3 and extending arcuately from beneath the bottom ear 8 following approximately the contour of the throat 16 to the end of the shelf 20, as will best be understood by a comparison of Figures 11, 14 and 17; and the shelf 20 is reinforced by a rib 24 depending therefrom and having a segment 25 extending diagonally along the edge of the shelf 20 which, as above noted, extends diagonally with respect to the longitudinal vertical center plane of the coupler head.

The rib segment 25 extends along the edge of the shelf 20 beneath the throat 16 approximately midway between the longitudinal center plane of the coupler head and the merger of the front face of the throat 16 with the guard arm base radius.

Figure 14 illustrates both couplers 1 and 2 in a position of extreme upward angling, and it will be seen in this figure that the upper rear edges of the knuckles 10 contact each other and the lower forward edges of the knuckles 10 contact the front faces of the mating coupler heads at 28 thereby limiting such upward angling without contact between the forward edges of the shelves 20, thereby preventing damage thereto. It will be apparent that under a combination of vertical offset as in Figure 14 with vertical angling as in Figure 15, the limiting contact of the knuckle 10 shown at the right in Figure 15 will be against the web 22 of the shelf 20, and the web being set back from the face 28 permits increased angling while maintaining clearance between the outer faces of the shelves 20.

As shown in Figures 11, 16 and 17, each knuckle 10 is provided on the underside thereof with a lug 50 for reception of one end 52 of a coil torsion spring 54 positioned around the lower end of the pivot pin 14. The other end 56 of the spring is anchored in a suitable hole 58 (Figure 17) of the web 22 of the shelf whereby the spring is main-

tained under torsion tending to throw the knuckle 10 to its open position.

It will be apparent from reference to the various figures of the modification that this design of shelf provides satisfactory interlock by overlap of the shelf with the nose of the knuckle and affords ample strength by providing a reinforcing rib directly beneath the point of load while still maintaining proper clearance for full angling of a knuckle incorporating a torsion spring lug.

I claim:

1. A railway coupler head comprising knuckle pivot means and a guard arm, said head having a throat between the pivot means and guard arm, and a shelf carried by said head beneath the level of the guard arm and throat and projecting forwardly of the throat, said shelf comprising a rib depending therefrom and extending diagonally across the vertical center plane of the head beneath the mid point of the throat.

2. A railway coupler head according to claim 1, wherein the shelf comprises an upper surface, the forward edge of which is defined by said rib, said shelf comprising a surface sloping downwardly from said rib toward the guard arm.

3. A railway coupler head according to claim 1, wherein the shelf comprises an upper substantially horizontal surface, a lower substantially horizontal surface, and a surface sloping downwardly from the upper surface and connecting the latter to the lower surface.

4. A railway coupling comprising mated couplers, each having a coupler head with a knuckle engaged with a knuckle of the mated coupler along approximately vertical surfaces of said knuckles accommodating relative vertical movement between said knuckles during relative vertical movement of the heads, each head having a throat extending from its knuckle beyond its longitudinal center line and adapted to engage the knuckle of the other head, a substantially vertical web depending from each head and offset rearwardly from its throat, and a shelf connected to the web and underlying the knuckle of the other head and spaced therebelow a distance less than the knuckle depth, the lower forward edges of the knuckles being engageable with the throats above the webs of respective heads during interengagement of the upper rear edges of the knuckles under conditions of extreme upward angling of both couplers unaccompanied by relative vertical offset therebetween.

5. A railway coupler comprising a head, a knuckle pivoted thereto, a guard arm, said head having a throat between the knuckle and guard arm, and a shelf carried by said head beneath the level of the guard arm and throat and projecting forwardly of the throat, said shelf comprising an approximately vertical rib depending therefrom and extending diagonally across the vertical center plane of the head beneath the mid point of the throat, said shelf having an upper level, the forward edge of which is aligned with the forward edge of the rib.

6. A railway coupler according to claim 5, wherein the shelf comprises a surface sloping downwardly from said upper level toward the guard arm.

7. A railway coupler according to claim 6, wherein the lower edge of said downwardly sloping surface is connected to a substantially horizontal surface of said shelf, said last mentioned surface partially underlying the guard arm.

8. A railway coupler head having top and bottom knuckle pivot ears at one side thereof and having a guard arm at the other side there-

of, said head having a throat extending from the ears to the guard arm, and a shelf integrally formed with the head beneath the level of the throat and projecting forwardly thereof, said shelf comprising a depending rib extending diagonally across the vertical center plane of the head beneath the mid-point of the throat.

9. A railway coupler head having top and bottom knuckle pivot ears at one side thereof and having a guard arm at the other side thereof, said head having a throat extending from said ears to said guard arm and having a ledge beneath said throat, said ledge having a forward surface defining a vertical plane approximately tangential to the bottom ear, and said ledge having another forward surface defining a vertical plane approximately tangential to a pin hole through the bottom ear.

10. A railway coupler head having top and bottom knuckle pivot ears at one side thereof and having a guard arm at the other side thereof, said head having a throat extending from said lugs to said guard arm and said head having a rib beneath said throat integrally formed with and extending between the lower surface of the bottom ear and the lower edge of the throat at a point on the throat approximating the point of tangency of the throat with the base radius of the guard arm.

11. A railway coupler head, according to claim 10, wherein the diagonal forward edge of the rib is disposed at an angle of between 30° and 40° with respect to the longitudinal vertical center plane of the coupler head.

12. A railway coupler head, according to claim 11, wherein the diagonal forward edge of the rib is so disposed that a straight line extended along this edge toward the bottom ear would pass outwardly of tangent to the ear edge, a distance between one-third and one-fourth of the depth from the center of the pivot hole in the ear to the edge of the ear.

13. A railway coupler head having top and bottom knuckle pivot ears at one side thereof, said head having a guard arm at the other side thereof, said head having a throat extending from said lugs to said guard arm and having a ledge beneath said throat integrally formed with and extending between the lower surface of the bottom ear and the lower edge of the throat at a point on the throat spaced from the longitudinal vertical center plane of the coupler head a distance less than the point of tangency of the throat with the base radius of the guard arm.

14. A railway coupler head having top and bottom knuckle pivot ears at one side thereof and having a guard arm at the other side thereof, said head having a throat extending from said lugs to said guard arm and having a substantially vertical web extending from the bottom ear and following the contour of the throat across the longitudinal vertical center plane of the coupler head, a ledge carried by said web and projecting forwardly beneath the throat, a knuckle having a portion between said ears, a pivot pin passing through aligned openings of said portion and ears, a torsion spring sleeved over the lower end of said pin, said spring having one end thereof anchored to the knuckle for resiliently urging the latter to open position thereof, and means on said web beneath the bottom ear anchoring the other end of said torsion spring.

15. A railway coupler head having top and bottom knuckle pivot ears at one side thereof and having a guard arm at the other side thereof, said aligned pivot pin holes through said ears, said

head having a throat extending from said lugs to said guard arm and having a ledge beneath said throat integrally formed with and extending between the lower surface of the bottom ear and the lower edge of the throat, the extreme forward face of the ledge being substantially tangential with the front of the pivot pin hole in the bottom ear, said ledge having a diagonal face connected to said forward face by a radial section and extending to the throat.
